CONTAINER

Oliver B. Andrews, Chattanooga, Tenn.

Application September 5, 1935, Serial No. 39,213

1 Claim. (Cl. 229—23)

This invention relates to containers, and particularly to containers constructed of paperboard or like material and having the form of a chest or locker.

One embodiment of the present invention relates to a container or box especially suitable for containing gifts, such as toys, games or similar articles, for presentation to children, which container may be used subsequently as a receptacle or chest for toys or games. In a box used for this purpose it is necessary that the box be strong enough to withstand rough handling, that it be so constructed as to withstand exposure to moisture, and preferably provided with such locking means that unauthorized access cannot be obtained thereto by children.

Another embodiment of the invention relates to a container of attractive and novel construction, having the form and properties of a chest or locker, and which is especially adapted for use as a container for foods, particularly such foods as cookies, crackers, candies, cakes and the like.

A feature of the invention consists in the provision of a locker-like container of relatively heavy paperboard material, having suitable locking means for the cover of the container, whereby the same may be locked by means of a padlock or similar means.

Another feature of the invention consists in forming a container of the class described, of two pieces of paperboard material of generally similar width, which pieces are adapted to be printed with suitable decorative or educational pictorial representations.

Still another feature of the invention consists in forming a paperboard container in simulation of, and having several of the characteristics of, a chest or locker.

The invention also consists in forming a product having the general characteristics, the new and useful applications, and the several original features of utility hereinafter set forth and claimed.

In the accompanying drawings there is shown for purposes of illustration one form of a device embodying the invention, in which

Fig. 1 is a plan view of a cut and scored blank employed in constructing a container according to the invention;

Fig. 2 is a similar view of another blank employed in constructing the container;

Fig. 3 is a perspective view of a partially completed container;

Fig. 4 is a perspective view, partially in cross-section, of a completed container;

Fig. 5 is a perspective view of the completed container with the cover closed and locked in place;

Fig. 6 is an enlarged fragmentary cross-sectional view showing the details of the locking arrangement;

Fig. 7 is a top plan view of a blank employed in constructing another embodiment of the invention;

Fig. 8 is a fragmentary view, partially in cross-section, of the completely set-up container;

Fig. 9 is a perspective view of the completely set-up container with the cover closed; and

Fig. 10 is a fragmentary view of a modification of the container shown in Figs. 7 to 9.

In one embodiment of the invention the container is formed from two blanks or strips 1 and 2 of heavy paperboard stock, which strips preferably are of generally similar width. The blank 1 is provided with equally-spaced score lines 3, 4 and 5 which divide the blank into substantially equal sections 10 to 13. Integral with and extending from the sides of sections 10, 11 and 12, 25 are flaps 16 and 17, 18 and 19, 20 and 21, respectively, and the score lines 22 to 27 are provided between these flaps and the sections 10, 11 and 12 to permit bending of these flaps. The flap 29 extends from the section 10, and the score line 28 permits bending of this flap.

The section 13 is provided with a perforation 31 adjacent one edge and lying on the longitudinal center-line of the strip 1, and the flap 29 is provided with a slot 30 also lying on the center-line of the strip.

The blank or strip 2 is rectangular, and is provided with score lines 35 and 36 which divide the blank into three equal sections 37, 38 and 39. Adjacent one longitudinal edge of the strip, and lying on the transverse center-line of the middle section 38, is a perforation 40 similar to the perforation 31.

The container is assembled by securing the free end of the section 37 to the flap 18, and the free end of the section 39 to the flap 19 by means of metal staples 50. Thus, a flat tubular construction is provided with the sections 10, 12 and 13 of the blank 1 attached thereto and extending therefrom. The container may be shipped or stored in this flat condition, and set up whenever desired.

The container is set up as follows: The blank 1 is bent along the score lines 22 to 27 inclusive, so that the flaps 16 to 21, inclusive, and 26 stand

up perpendicularly to their respective sections of the blank. Thereafter, the section 13 is drawn through the tube constituted by section 11 of blank 1, and sections 37, 38 and 39 of blank 2, the flaps 20 and 21 being tucked inside of the sections 37 and 39, respectively.

It will be seen now that the section 11 constitutes a rear wall, section 12 constitutes a bottom, sections 37 and 39 constitute side walls and section 38 constitutes a front wall. Also, section 10 constitutes a cover and section 13 a front flap which lies along and reinforces the front wall 38. It will be noted that when the box is set up, the perforations 31 and 40 are brought into alignment, and an opening 65 extending entirely through the front wall is provided.

When the container has been set up, as described, circular crimp washers 60 and 61 are disposed in registry with the opening 65 on both sides of the front wall respectively, and an eye screw 62 is projected through the opening. A nut 63 is thereafter threaded thereon to secure the eye screw 62 and at the same time to draw the crimp washers 60 and 61 together, and thereby securely hold the flap 13 and the front wall 38 in intimate abutting engagement.

When desired, the cover 10 may be closed, the flaps 16 and 17 being tucked inside the side walls 37 and 39, and the flap 29 being left outside of the container to overlie the upper portion of the front wall 38. When the cover is closed, the slot 30 is in registry with the opening 65, and receives the eye portion of the eye screw 62. Due to the natural resiliency of the material, there is a slight tendency for the cover to be forced upwardly at the forward portion, and thus the flap 29 is in hooked engagement with the eye screw 62 and the cover is maintained in closed position. Preferably, unauthorized entry of the container may be prevented by a padlock 64, the hook portion of which is passed through the eye of the eye screw 62.

In another embodiment of the invention, the container is constituted by a single piece or blank 70 of paperboard, for example, corrugated paper, which is cut in the general shape of the letter T. In one portion of the blank 70, substantially equal sections 71, 72 and 73 are defined by score lines 74, 75, 76, and 77. Integral with and extending from the sections 71 and 73, are flaps 78 and 79, respectively. In the other portion of the blank 70, sections 90, 91 and 92 are defined by score lines 93, 94 and 95, and integral with and extending from corner portions of these sections are leg extensions 100 to 103. The extensions 101 and 102 are full leg extensions, and score lines 94 and 95 respectively extend through the centers of these legs. The leg extensions 100 and 103 are of half-leg form, as will be seen. The leg extension 100 is separated from section 73 by a cut line 104.

The container is formed into a tubular construction by bringing the edge of the section 92 into abutment with the edge of the section 72, and adhesively applying to the adjacent marginal portions of these sections a cloth or paper tape 111. This tubular construction tends normally to lie flat, and the container may be shipped and stored in this condition.

70 A piece of tape 112, bearing adhesive on one side, is adhesively secured to the flap 79 at the central portion of the edge, and a substantial portion of the tape is permitted to extend beyond the edge of the flap 79, for a purpose hereinafter 75 explained.

When it is desired to set up the container, the blank is bent along all of the score lines, and the flap 79 is tucked within the tube constituted by sections 72, 90, 97 and 92, and lies against the inner surface of section 97. The overhanging portion 114 of the tape 112 is adhesively secured to the inner side of the section 97 to maintain the section 73 in position to constitute a bottom for the container. The container is now ready for use, and may be closed by tucking the flap 10 78, which serves as a tongue, into the container against the inner surface of the section or front wall 97, as shown.

It will be seen that, when the section 73 is in position to form a bottom wall for the container, 15 the leg portions 100 to 103 constitute four spaced legs upon which the container may be supported, which legs extend below the bottom wall in a manner somewhat similar to the legs of a "treasure chest".

If desired, a stop means may be provided for preventing the forward portion of the cover from being forced down into the container proper and to maintain the cover in the plane of the top edges of the side walls. Such means may be provided, as shown in Fig. 10, by forming the flap 78a and the flap 79a of such respective lengths that their edges meet in abutting relation when the cover is in closed position, the edges of the flap 79a thus serving as an abutment for the flap 78a.

A substantially semi-circular notch 110 is provided in the upper edge of the section 97 for the purpose of permitting a grip to be obtained upon the flap 78 when the cover is closed, to facilitate 35 raising the cover.

It will now be seen that the container provided by the present invention is simple, rugged and capable of simple and inexpensive fabrication and of such construction that the preliminary 40 forming operations may be carried out and the partially formed container stored or shipped in flat folded condition, and set up when desired by a simple operation which does not necessitate the use of any instrumentalities other than the hands 45 of the user.

It will likewise be seen that since the front flap is integral with the section which forms the bottom of the container and lies against the front wall, it serves not only as means for maintaining the bottom in proper position, but also as means for reinforcing the front wall. In the embodiment shown in Figs. 1 to 6, this feature is of great importance, in that it permits the installation of a metal locking arrangement of 55 the paperboard container without incurring the liability of defacement or destruction of the container.

The construction of the container of stiff paperboard material, and the provision of a metal 60 lock therefor prevent unauthorized opening of the container without the exercise of considerable force or the use of a cutting means such as a knife. Thus the container is quite safely locked against intrusion by children, inasmuch as it 65 can be made strong enough to resist ordinary attempts to destroy the same, and since it is not generally customary to provide children with sharp instruments of the type necessary to obtain access to the container by cutting through 70 the same.

The absence of glue, paste or similar securing means permits the box, if formed of suitable waterproofed material, to be subjected to wetting, such as rain and the like, without destruction of 75

the container, or without the opening of any of the seams.

In the embodiment of the invention shown in Figs. 7 and 9, the provision of supporting legs 5 extending from the side walls,—which legs support the bottom wall an appreciable distance above the shelf or other means upon which the container may be disposed—permits circulation of air under and around the container, and prevents the bottom wall from being moistened in the event that the container is disposed upon a wetted surface. Thus this container is especially adapted for containing food stuffs which are spoiled by absorbing moisture, or by the failure to maintain suitable circulation of air thereabout.

It will be obvious that the container may be modified in various ways without departing from the spirit of the invention. The blanks may be formed from various kinds of paperboard or equivalent material, depending upon the use for which the container is intended. The invention is not limited to containers of any particular size, but is applicable to various sizes of containers and to shapes other than cubical. When a container of the type disclosed in Figs. 7-9 is used for foods, preferably corrugated paperboard of the type shown is used, and the container is of convenient size for storage in cupboards and the like.

Also, it should be apparent that a container constructed according to the invention is not limited to the uses specifically set forth, but may be employed for a very large variety of uses, which will suggest themselves to those skilled in the art.

What is claimed is:

A foldable container, including relatively rigid paperboard panels secured together and defining bottom, front, rear and end walls, a top cover integrally and flexibly connected to the edge of said rear wall and having flaps extending from the free edges thereof and positioned to overlie the top edges of the corresponding front and end walls when the top cover is closed, a member extending along said front wall for reinforcing and stiffening at least the top and bottom edges thereof, metallic fastening means extending through said front wall and said reinforcing member for securing said reinforcing member in position, means extending substantially throughout the height of said end walls for reinforcing and stiffening said end walls adjacent said rear wall, flaps extending from the end edges of said bottom wall and means securing said top cover flaps and bottom flaps in closed position whereby said container is reinforced and stiffened along all end edges and along both top and bottom edges of said front wall.
